(57) **CLAIM**

The ornamental design for a storage container with two lids, as shown.

DESCRIPTION

FIG. 1 is an upper perspective view of a first embodiment of a storage container with two lids with the lids of the storage container closed;

FIG. 2 is a lower perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an upper perspective view of the first embodiment of the storage container with two lids with the lids of the storage container open;

FIG. 10 is a lower perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is an upper perspective view of a second embodiment of the storage container with two lids with the lids of the storage container closed;

FIG. 18 is a lower perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof;

FIG. 25 is an upper perspective view of the second embodiment of the storage container with two lids with the lids of the storage container open;

FIG. 26 is a lower perspective view thereof;

FIG. 27 is a front view thereof;

FIG. 28 is a rear view thereof;

FIG. 29 is a left side view thereof;

FIG. 30 is a right side view thereof;

FIG. 31 is a top view thereof; and,

FIG. 32 is a bottom view thereof.

The broken lines in the drawings depict portions of the storage container with two lids that form no part of the claimed design.
